ROTATABLE MISSAL STAND

Joseph J. Gildea, The Monastery, Villanova, Pa. 19085

Filed Oct. 2, 1967, Ser. No. 8,822

Term of patent 14 years

(Cl. D33—3)

FIGURE 1 is a plan view of a rotatable missal stand showing my design.

FIGURE 2 is a side elevation of one of the sides of the stand.

FIGURE 3 is an elevational view of the side of the stand remote from that shown in FIGURE 2.

FIGURE 4 is a bottom plan view of the missal stand.

FIGURE 5 is an elevational view of the front of the missal stand, which is identical to an elevational view of the back of the stand.

I claim:

The ornamental design for a rotatable missal stand, substantially as shown and described.
